[57] **ABSTRACT**
A method of decreasing the involuntary movements associated with cerebral palsy using clorazepate dipotassium as the active agent.

1 Claim, No Drawings

**METHOD OF REDUCING INVOLUNTARY
MOVEMENTS ASSOCIATED WITH CEREBRAL
PALSY USING CLORAZEPATE DIPOTASSIUM**

This invention relates to a method of reducing and/or controlling the involuntary movements associated with cerebral palsy using clorazepate dipotassium as the active agent.

The compound useful in the practice of this invention is represented by the formula

The compound can be prepared according to Example 35 of U.S. Pat. No. 3,516,988.

Clorazepate dipotassium, the dipotassium salt of 7-chloro-2,3-dihydro-2-oxo-5-phenyl-1H-1,4-benzodiazepine-3-carboxylic acid, has previously been reported to be useful as an anticonvulsant agent, anti-depressant, muscle relaxant, antianxiety agent and as a tranquilizer. (See, for example, U.S. Pat. No. 3,516,988).

10 It has now been unexpectedly found that when clorazepate dipotassium is administered to cerebral palsy patients in oral doses of from 15 to 90 mg. per day, the involuntary movements associated with cerebral palsy are either greatly reduced or are completely stopped.

15 The marked reduction or cessation of involuntary movements are sustained when the patient is maintained on clorazepate dipotassium.

I claim:

20 1. A method of reducing the involuntary movement associated with cerebral palsy comprising orally administering to a cerebral palsy patient from 15 to 90 mg. daily of clorazepate dipotassium.
